UNITED STATES PATENT OFFICE.

GUSTAV A. SPELBRINK, OF IVANHOE, MINNESOTA.

GRAIN-CAR DOOR.

1,233,818.

Specification of Letters Patent. Patented July 17, 1917.

Application filed June 5, 1916. Serial No. 101,718.

To all whom it may concern:

Be it known that I, GUSTAV A. SPELBRINK, a citizen of the United States, and a resident of Ivanhoe, in the county of Lincoln 5 and State of Minnesota, have invented a new and Improved Grain-Car Door, of which the following is a full, clear, and exact description.

My invention has for its object to provide 10 a grain car door which is inexpensive to manufacture and one which will not permit leakage while so constructed that it may be easily operated. Novel means are provided for holding the door spaced from the door 15 frame when ready for rotation and also for holding the door out of the way when in open position.

Additional objects of the invention will appear in the following specification, in 20 which the preferred form of the invention is described.

In the drawings, similar reference characters refer to similar parts in all the views, in which—

25 Fig. 1 is a sectional view showing a portion of the interior of a car provided with my grain car door;

Fig. 2 is a sectional view on the line 2—2 of Fig. 1;

30 Fig. 3 is a sectional view on the line 3—3 of Fig. 1;

Fig. 4 is a fragmentary view of the car showing my door looking from the exterior of the car; and

35 Fig. 5 is a fragmentary sectional view showing the means for rotating one of the rods provided with an eccentric on which one of the door members is mounted.

By referring to the drawings, it will be 40 seen that the car body 5 has a door frame having sides 6 and 7, there being a metal plate 8 at the side 6 of the door frame, this metal plate at the inner side of the door frame extending laterally at 9, a flange 10 45 projecting from the lateral portion 9 of the plate 8 in the general direction of the side 7 of the door frame. Against the said side 7 of the door frame there is a plate 11 provided with a shoulder 12. Bearings 13 are 50 mounted on the car at the side 7 of the door frame, a rod 14 being journaled in these bearings 13 and being provided with an eccentric 15 on which the hinges 16 are slidably mounted, these hinges 16 being fastened to the door member 17 which is provided with a flange 18 for disposal between

the flange 10 and the laterally extending portion 9 of the plate 8. Disposed adjacent the side 6 of the door frame there is a rod 19 journaled in bearings 20, the rod 19 being provided with an eccentric 21 on which are slidably mounted the hinges 22, the said hinges 22 being fastened to the door member 23. This door member 23 is provided with a flange 24 for disposal between 60 the flange 10 and the laterally extending portion 9 of the plate 8.

It will be understood that with this construction the door member 17 may be moved substantially to a closed position when by a 70 rotary movement of the rod 14 its flange 18 may be disposed in the position indicated in Fig. 2 of the drawings to lock the door member 17 at its flange 18 and prevent any possible leakage at this point. In a similar 75 manner the door member 23 may be moved substantially to closed position when the rod 19 may be rotated thereby permitting the movement of the flange 24 between the flange 10 and the lateral portion 9 of the 80 plate 8 after which the door 23 may be pushed into place against the shoulder 12 on the plate 11, which will prevent any leakage between the said plate 24 and the side 6 of the door frame.

When the door members 17 and 23 have been moved to closed positions the latch 25 pivoted at 26 to the door member 23 may be moved to the position indicated in Fig. 1 of the drawings where it will have its 90 terminal disposed in locking position with the eccentric 15 of the rod 14. To prevent lateral displacement of the latch 25 when in locked position, I provide a guard 27 which engages the latch 25 to hold it in 95 place. As the latch 25 is adjacent the top of the doorway it may be readily opened from the top of the door member 23. To the top of the rod 14 there is secured an arm 28 by means of which the rod 14 may be 100 rotated to free the flange 18 on the door member 17 from the flange 10. It will, therefore, be understood that after the latch 25 is freed from the rod 14 that the door member 23 may be slightly opened when it 105 will be possible to move the door member 23 laterally with its flange 24 out of engagement with the flange 10, after which the door member 23 may freely move the hinges 22 permitting the operator to swing the 110 door member 23 in a complete half circle, when the door member 23 may be raised

with the hinges 22 so that it may be supported on the bracket 29 in position indicated by dotted lines in Fig. 1 of the drawings. When the rod 14 has been rotated by 5 the arm 28 it will move the flange 18 out of engagement with the flange 10, after which the door member 17 may be completely opened and be moved upwardly with the hinges 16 sliding on the rod 14 to the position 10 indicated in Fig. 1 of the drawings where it may be supported on the bracket 30. A keeper 31 is provided for holding the arm 28 in locked position.

There are auxiliary doorways 32 in the 15 door member 17, these auxiliary doorways 32 being normally closed by means of auxiliary doors 33 which are hinged at 34 and are normally held in closed position by latches 35.

20 The flange 18 has a bent side 18^a, and at the other side of the door member 17 there is a plate 36 which is bent to fit the shoulder 12, this plate having a bent side 36^a; the said bent sides 18^a and 36^a being connected by 25 braces 37. In a similar manner braces 38 connect the bent side 24^a of the flange 24 and the bent side 39^a of the plate 39.

Having thus described my invention, I 30 claim as new and desire to secure by Letters Patent:—

1. In a grain car door, a door frame having a side with a flange extending in the general direction of the opposite side of the door frame, two rods pivoted one at each 35 side of the door frame, the rods being each provided with an eccentric, two doors normally disposed one above the other, flanges on the doors for moving with the said doors longitudinally of the door frame to positions 40 where the second mentioned flanges will interlock with the first mentioned flanges,

hinges secured to one of the doors and slidably mounted on one of the eccentrics, hinges secured to the other door and mounted on the other eccentric, an arm disposed above 45 the normal position of the doors and secured to the rod having the eccentric to which the lower door is hinged, and a latch on the upper door for engaging the last mentioned rod.

2. In a grain car door, a door frame having a side with a flange extending in the direction of the opposite side of the door frame, two rods pivoted one at each side of the door frame parallel therewith, the rods 55 being provided with eccentrics, two doors normally disposed one above the other, flanges on the doors for moving with the doors longitudinally of the door frame to positions where the second flanges will interlock with the first flange, and hinges secured to the doors and slidably mounted on the eccentrics.

3. In a grain car door, a door frame having a side with a flange extending in the 65 direction of the opposite side of the door frame, two rods pivoted one at each side of the door frame parallel therewith, the rods being provided with eccentrics, two doors normally disposed one above the other, 70 flanges on the doors for moving with the doors longitudinally of the door frame to positions where the second mentioned flanges will interlock with the first flange, hinges secured to the doors and slidably mounted 75 on the eccentrics, locking means on the free end of one of the doors for engaging the rod adjacent thereto, and means normally disposed above the doors for rotating the last-mentioned rod.

GUSTAV A. SPELBRINK.

Copies of this patent may be obtained for five cents each, by addressing the "Commissioner of Patents, Washington, D. C."
